UNITED STATES PATENT OFFICE

JESSE E. ESHBAUGH, OF FLINT, MICHIGAN

OXYGEN GAS SUPPLY SYSTEM

Application filed April 11, 1931. Serial No. 529,527.

This invention has reference to improvements in oxygen gas supply systems for aeronautical use.

Due to the rarity of the air at high altitudes it is necessary to supply airplane pilots with oxygen for breathing purposes when they go above a certain height which may vary somewhat with the individual. The oxygen gas is stored and carried on the planes in small steel cylinders at a predetermined pressure and the flow to the pilots is controlled by some type of regulator.

At times, however, the regulator fails to function or does not function properly. This liability of the instrument becoming inoperative may be due to faulty equipment, aneroid failure, or to the small orifices in the regulator becoming plugged with ice or dirt particles so that the normal path of the gas through the system becomes obstructed and the pilot is thereby deprived of a sufficient supply of oxygen.

It is the object of the present invention to relieve the pilot of the danger and discomforts attending the failure of the regulator by incorporating in the system an auxiliary or emergency device by the operation of which the pilot is assured of an adequate supply of oxygen in case the oxygen regulator ceases to function properly.

With this object in view, the invention consists in the novel combination, arrangement and construction of parts hereinafter more fully described and pointed out with reference to the accompanying drawings, wherein;

Figure 1 is a diagrammatic view of an oxygen supply system showing the path of the fluid under normal operating conditions;

Figure 2 is a similar view showing the path of the fluid when the normal flow is obstructed;

Figure 3 is a front elevation of the emergency valve assembly forming part of the invention;

Figure 4 is a top plan view of the valve assembly;

Figure 5 is a vertical longitudinal section 50 on line 5-5 of Fig. 3, and

Figure 6 is a perspective view of the valve core.

Briefly described, the invention embodies an oxygen supply system wherein a direct passage from the oxygen supply to the low pressure tubing running to the mouthpiece or mask of the person using the oxygen is provided through a by-pass and a by-pass valve the operation of which, in event of failure of the regulator, will provide a positive flow of gas by piercing a diaphragm through which the gas may pass. The invention is herein shown and described in application to a Prouty oxygen regulator but is equally applicable to other types of regulators.

The oxygen supply is contained in an oxygen cylinder 1 and when the cylinder valve 2 is opened, it flows to the high pressure side of the Prouty regulator 3 through the high pressure oxygen tubing 4. The showing of the Prouty regulator is merely conventional as the construction and operation thereof is well understood in the art. From the opposite or low pressure side of the regulator, the oxygen passes into the supply line or low pressure tubing 5 leading to a mouthpiece 6 or to the mask of the person using the oxygen. Due to the fact that, in all standard types of oxygen gas apparatus in present use, no gas from the supply cylinder passes into the mouthpiece tube except by way of the regulator, a failure on the part of the latter results in the cutting off of the necessary supply of oxygen to the pilot. In the present invention, however, the mouthpiece tube is provided with a by-pass valve including a valve casing 7 having a tapered bore in which is rotatably seated a close fitting correspondingly tapered valve core 8 having at one end an operating handle 9 and at its other end being provided with a flat sided shank or stem 10. Encircling the shank and confined between washers 11 and 12 is a valve tensioning spring 13. The spring and washers are retained upon the shank by suitable means, such as a cotter pin 14. The valve has an inlet passage 15 and an outlet passage 16 to which are connected upper and lower sections *a* and *b* 103

respectively of the mouthpiece tubing 5. Adjacent the inlet passage 15 and horizontally offset with respect thereto is a vent passage which opens outwardly to the atmosphere through the vent tube 17. Between the inlet and outlet passages of the valve casing, a lateral or by-pass passage 18 is provided.

The valve core 8 has a central passageway 19 adapted in the normal position of the valve to register with the inlet and outlet openings of the valve casing, as shown in Fig. 1. The inlet end of the central passageway is enlarged, as shown at 20, and partially cut away on one side to provide a port 21 leading to a cam groove or channel 22 formed in one side of the core. On its opposite side, the core is also grooved to provide an L-shaped channel or conduit 23. Disposed within the by-pass passage 18 of the valve casing with its inner end protruding into the cam groove of the valve core is a freely movable plunger 24 having a tapered or pointed outer end.

The by-pass passage 18 is reduced at its outer portion to provide a shoulder or seat 25 for a diaphragm 26 which is held to its seat by the inner end of a nipple 27 threadedly engaged within the outer portion of the passage and having attached thereto one end of a by-pass tube 28. The other end of the tube 28 is suitably connected with the high pressure tubing 4. The valve and tubing 28 constitute a by-pass and are intended to function as an auxiliary or safety device in the event the normal path of the fluid through the system becomes obstructed.

The operation of the improved system is as follows: Figure 1 shows the path of the fluid through the valve under normal operating conditions. Should the flow of oxygen to the pilot become obstructed because of the impairment or failure of the regulator, the valve core 8 is turned 90° clockwise to the position shown in Figure 2, placing the enlargement 21 of the valve core passage 19 in registry with the by-pass passage 18 and the lower terminal of the cam groove in registry with the outlet opening 16 of the valve. As the core is turned, the plunger 24 riding on cam 22 is moved outwardly against the diaphragm 26, and pierces the latter to provide an opening through which the fluid from the by-pass tubing is admitted directly into the valve, passing by way of port 21 and cam groove 22 to the outlet 16 of the valve and thence into the mouthpiece tube 5b. The pressure of the fluid acting against the forward end of the plunger is sufficient to force the latter backwardly from the punctured diaphragm and into seating engagement with the enlarged recess 20 when the latter is opposite the passage 18. Since the diameter of the plunger is considerably less than that of

the passage 18, the fluid flows easily around the same and into the cam groove. At the same time, channel 23 connects passage 15 with the vent passage 17 for the protection against excess pressure of that part of the system which is temporarily thrown out of use. Since the fluid which might otherwise accumulate in the regulator is permitted to escape through the vent, the building up of a dangerous or disastrous pressure in the regulator is thereby prevented. The amount of fluid which is obtained by means of the by-pass valve is determined by the size of hole which is pierced in diaphragm 26, which in most cases will give ample regulation. The diaphragm may be tightly sealed so there will be no loss by leakage before it is used.

From the foregoing it will be seen that the invention provides an emergency safety device for altitude flights in the nature of a by-pass and valve which in case of failure of the regulator will provide a positive flow of gas by piercing a diaphragm through which the gas may flow to the pilot or operator in need of the oxygen. The operation and application of the device is simple and efficient and various modifications thereof may be adopted within the scope of the appended claims.

I claim:

1. A by-pass valve comprising a valve casing having main inlet and outlet passages, a by-pass inlet passage, and a vent passage, a rotatable valve core having a through passage normally connecting the said main inlet and outlet passages, a by-passage for connecting the by-pass inlet passage with the main outlet passage and a vent conduit for connecting the main inlet passage with the said vent passage, a diaphragm closing the said by-pass inlet passage, a plunger in said by-pass inlet passage, and a cam on valve core for moving said plunger against the diaphragm to puncture the same.

2. An oxygen gas supply system including a source of oxygen supply, a flow-regulator connected with the said source of oxygen supply, a delivery tube connected with said flow-regulator, an auxiliary conduit directly connecting the oxygen supply source with the said delivery tube and by-passing the said flow-regulator, and a two-way control valve at the junction of the auxiliary conduit and the delivery tube having an open-air vent adapted to be placed into communication with the said flow-regulator automatically upon turning the valve to open the auxiliary conduit.

3. An oxygen supply system including a source of oxygen gas, an oxygen flow regulator, a high pressure line connecting the regulator with the said source, a mouthpiece, a low pressure line connecting the regulator with the mouthpiece and includ-

ing a normally closed vent and a normally opened valve relatively and operatively connected so that the closing of the valve opens the said vent, a normally closed emergency 5 line connecting the said source with the said mouthpiece by way of the said low pressure line and by-passing the said regulator, and means for opening the said emergency line, said means being operatively connected with 10 the said valve to be actuated automatically thereby and coincident with the closing of the said valve.

4. An oxygen supply system including a source of oxygen gas, an oxygen flow regulator 15 in communication with said source, a delivery tube leading from said flow regulator, an auxiliary sealed conduit directly connecting the said source to the said de-

livery tube and by-passing the said flow regulator, a mouth piece at the end of the tube, a valve in said tube for cutting off communication between the mouth piece and the said flow regulator, means for breaking the seal 70 of the auxiliary conduit, said means being operatively connected with the valve to be actuated by the movement of the valve into position cutting off communication between mouthpiece and flow-regulator, and venting 75 means for placing the flow regulator in communication with the atmosphere simultaneously with the cutting off of its communication with the mouthpiece, said venting means being operatively associated with the said 30 valve for actuation thereby.

In testimony whereof I affix my signature.
JESSE E. ESHBAUGH.
